[57] CLAIM

The ornamental design for fuel pump for an engine for a model, as shown.

DESCRIPTION

FIG. 1 is a front elevational view of a fuel pump for an engine for a model showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof; and

FIG. 8 is a view showing how the article of design is used. In the figure, the fuel pump 4 of the present design is connected to a fuel tank 7 through an inlet port 1, to a crank room of an engine 5 for a model through a pressure port 3, and to a carburetor 6 through an outlet port 2.
